UNITED STATES PATENT OFFICE.

EDWARD HART, OF EASTON, PENNSYLVANIA, ASSIGNOR TO HIMSELF,
JOHN TOWNSEND BAKER, AND GEORGE PURSEGLOVE ADAMSON, OF
SAME PLACE.

ACID-BOTTLE.

SPECIFICATION forming part of Letters Patent No. 423,683, dated March 18, 1890.

Application filed August 26, 1889. Serial No. 321,956. (No model.)

To all whom it may concern:

Be it known that I, EDWARD HART, of Easton, in the county of Northampton and State of Pennsylvania, have invented a new and useful Improvement in Acid-Bottles, of which the following is a full, clear, and exact description.

My invention relates to an improved acid-bottle especially adapted for the storing and transportation of hydrofluoric acid in pure condition. This is done at present in leaden or in rubber bottles or other containing-vessels made of the same materials.

It is well known that hydrofluoric acid will destroy glass and will attack both lead and rubber—slowly, it is true, but still rapidly enough to render the acid contained in such vessels useless for analytical or other purposes where perfectly pure acid is necessary.

It is the object of the present invention to provide a receptacle which will not be affected in the least by hydrofluoric acid. Platinum is sometimes used in the manufacture of such a receptacle; but it is far too expensive for general use.

My invention consists in constructing a bottle or other receptacle to be used as an acid-bottle entirely of wax, paraffine, or ceresine, sometimes called "ozokerite" or "mineral wax," or mixtures of these substances.

Reference is to be had to the accompanying drawings, forming a part of this specification, in which similar letters and figures of reference indicate corresponding parts in all the views.

Figure 1 is a central vertical section through a mold, illustrating the manner of producing the receptacle; and Fig. 2 is a transverse section through the mold and the receptacle contained therein. Fig. 3 is a side elevation of the bottle, partly in section, illustrating the position of the stopper when the bottle is in use; and Fig. 4 is a similar view illustrating the position of the stopper just prior to sealing the bottle for transportation.

Neither of the substances above set forth—namely, animal wax, paraffine, or ceresine—is attacked in the least by the acid in its pure condition; but animal wax is very expensive, and is preferably not used alone.

Paraffine is the cheapest; but in order to prevent crystallization and consequent danger of leakage one or the other of the above-named substances should be added thereto. I prefer, however, to use ceresine, as it melts at a high temperature.

By experiment I have found that the best mode of constructing the vessel is that illustrated in Figs. 1 and 2, which consists in a mold constructed in two sections 10 and 11, having an orifice at the top and a tapering stopper 12, adapted to fit the said orifice. This mold may be made of plaster-of-paris, metal, or other approved substance, and the inside of the mold is shaped to the exterior of the bottle or receptacle to be cast. The molten material is poured into the mold through the orifice therein and the stopper 12 is then fixed to place, whereupon the mold is rapidly shaken, or a centrifugal motion is imparted thereto, whereby the heated liquid material is forced into contact with the interior surface of the mold at all points. This rotary or reciprocating motion is kept up until conge- 70 lation takes place. The result is a hollow casting 13, (illustrated in Figs. 3 and 4, for instance,) which may be made thick or thin at pleasure, according as more or less molten material is poured into the mold.

The stopper 14 of the receptacle is preferably made of a like material with the body, 80 and consists of a body a , adapted to fit loosely in the neck of the bottle, and an upper flange a' , concaved upon the upper face, as illustrated at 15 in Figs. 3 and 4.

In Fig. 3 the body of the stopper is illus- 85 trated as inserted in the mouth of the bottle or receptacle, and is so placed when the receptacle is in use.

When the bottle of acid is to be transported or stored, the stopper is inverted, as shown 90 in Fig. 4, whereupon the flange a' of the stopper contacts with the upper surface of the receptacle around the mouth.

The stopper and the body of the receptacle are cemented together by applying heat to 95 the flange of the stopper, thereby causing the latter to melt to an extent and forming a sealed joint with the body. To open the bot-

tle when so sealed, it is simply necessary to introduce a knife or other sharp instrument between the contacting surfaces of the bottle and the stopper.

5 Having thus described my invention, I claim as new and desire to secure by Letters Patent—

1. As an improved article of manufacture, an acid-bottle constructed of wax, substantially as shown and described.

2. In an acid-bottle, the combination, with a wax body, of a reversible stopper also constructed of wax, substantially as shown and described.

15 3. As an improved article of manufacture, an acid-bottle constructed of animal and mineral wax, substantially as shown and described.

4. As an improved article of manufacture, 20 an acid-bottle constructed of animal and mineral wax and provided with a stopper of the same material, as and for the purpose specified.

5. In an acid-bottle, the combination, with 25 a body constructed of animal and mineral

wax, of a reversible stopper of the same material, consisting of a body portion and a flange at one end of the same, substantially as and for the purpose specified.

6. In an acid-bottle, the combination, with 30 the body constructed of animal and mineral wax, of a reversible stopper comprising a body portion and a flange integral with one end of the said body, having a concaved outer face, substantially as and for the purpose 35 specified.

7. As an improved article of manufacture, a stopper for an acid-bottle, the same being constructed of wax and provided with a peripheral flange, substantially as and for the 40 purpose specified.

8. As an improved article of manufacture, a stopper for acid-bottles, constructed of animal and mineral wax, substantially as shown and described.

EDWARD HART.
